UNITED STATES PATENT OFFICE.

EDWIN R. SAGE, OF BALTIMORE, MARYLAND.

REFRIGERATION APPARATUS.

Application filed November 4, 1920. Serial No. 421,688.

To all who, it may concern:

Be it known that I, EDWIN R. SAGE, a citizen of the United States, and a resident of Baltimore, Maryland, have invented certain new and useful Improvements in Refrigeration Apparatus, of which the following is a specification.

My present invention relates to improvements in refrigerating machines designed to operate by the evaporation of water though not limited to the use of this particular liquid, and aims to produce an apparatus of greater simplicity and efficiency than any heretofore produced of which I am aware, and one which will be of greater economy in cost of production and operation.

With these and other objects in view, the invention includes the novel features of construction and arrangement and combination of parts hereinafter described and particularly defined by the appended claims.

My invention is illustrated in the accompanying drawings in which, for convenience and one manner of use I have shown it as embodied in a refrigerator of the household type, it being understood, however, that I do not limit myself to such use.

In these drawings—

Figure 1 is an elevation of a complete refrigerating apparatus.

Fig. 2 is a sectional elevation on a larger scale, of the compressor and condenser, or high pressure unit.

Fig. 3 is a transverse section on line 3—3 of Fig. 2.

Fig. 4 is an enlarged sectional detail of the water jet air pump.

Fig. 5 is an enlarged detail view in elevation of the motor control unit;

Fig. 5^a is a section on line x—x of Fig. 5.

Fig. 6 is a transverse vertical section, on line 6—6 on a larger scale than Fig. 1, through the evaporator or low pressure unit, which in the embodiment shown, is in the shape of a refrigerator chamber.

Fig. 7 is a diagrammatic view illustrating the electric circuits or connections.

Referring by reference characters to these drawings, the numeral 1 designates the refrigerator chamber which may be of any suitable size and shape and which is provided with three spaced walls indicated respectively at 1^a, 1^b and 1^c. Between the outer wall 1^a and the next inner wall 1^b is

placed any suitable material which is a good 55 heat insulator, indicated at 1^d.

The inner wall 1^c is spaced from the wall 1^b at sides, top and bottom, to provide a water chamber completely encircling the cooling chamber, and is supported therefrom 60 by struts 1^e.

Doors 1^f are provided for access to the cooling chamber, and shelves 1^g may be provided for the support of articles as is customary. The wall 1^c is provided, upon its 65 exterior face with a series of closely spaced trays ^h designed to be filled with water from the overflow of the liquid from each next upper tray, the evaporation of the liquid serving to effect the cooling of the contents 70 of the inner or cooling chamber.

The condenser or high pressure unit is indicated as a whole at 2 and is shown for convenience as mounted directly upon the top of the low pressure unit. 75

It comprises a circular hollow body having an annular inner wall 2^a which provides an inner chamber ^a, and an outer annular chamber ^{a'}, these chambers being closed at the bottom, except for the pipe connections 80 hereinafter described. Said bottom closure or wall is provided with a central opening in which is located a vertical pipe 3, the lower end of which communicates by a pipe 4 with a port formed in the bottom wall of 85 the chamber ^{a'}.

Encircling the pipe 3 and rotatable thereabout but spaced therefrom to provide a water overflow passage 3^a, is the tubular hub 5^a which is part of a hollow rotor 5 90 which rotor has an outwardly extending annular upper portion 5^d provided with fluid discharge passages indicated at 5^e.

The inner ends of these passages are substantially tangential to the inner wall of the 95 rotor; and from their inner ends the passages curve outwardly, terminating at their outer ends substantially radially of the rotor as shown in Fig. 3.

The passages are preferably elongated 100 vertically as shown. The direction of rotation of the rotor is indicated by the arrow, Fig. 3, the relation of the passages being such that as the rotor is rapidly rotated liquid water will be forced into the passages 105 and discharged therefrom at high velocity, due to centrifugal action.

The wall 2^a carries at its upper extremity,

preferably formed integral therewith, an annular series of diffuser passages at 6, which have their inner ends located in close proximity to the exterior surface of the upper portion 5^a of the rotor so as to receive the fluid jets discharged therefrom.

These passages are preferably arranged at an angle to the radii of the rotor, the inclination being such that each passage is in the same plane approximately as the direction of the liquid discharged from the rotor at the point of entrance of this passage and the said passages 6 are elongated vertically to correspond to those of the rotor.

The passages 6 discharge at their outer ends into the annular chamber or space a'.

Mounted in the upper part of the compressor element 2 which serves as a casing therefor, is an electric motor of any approved design, the motor shaft of which is shown at 7, which is fast to an upwardly extending hub portion 5^b of the rotor, said rotor being in fact preferably supported from the motor shaft.

The wall 2^a of the chamber a' is preferably carried upwardly and outwardly to join the outer wall of the compressor.

A pipe 8 connects the chamber a of the compressor or high pressure unit with the water chamber of the refrigerator unit.

A pipe 9 connects chamber a' with a suction pump by which, after sufficient water has been charged into the system, all air 35 may be removed, the interior of the system being reduced to as near a perfect vacuum as possible.

In the embodiment of the invention shown in the drawings the suction pump is 40 preferably in the form of a hydraulic ejector having a casing 10 with which the pipe 9 connects, which casing is provided with a valve seat 10^a having a check valve 11, access to which is permitted by the removable 45 plug 10^b. The air pump is in the shape of a water ejector nozzle 12 discharging into an aligned receiving member 13, the air being drawn by the ejector action from the interior of the casing in the manner well 50 understood by those skilled in the art. The member 13 is connected by pipe 14^a with a cooling and condensing coil 14 located within the chamber a', the water discharge being indicated at 14^b which may deliver to 55 waste at any convenient point.

The ejector nozzle 12 is connected by branch pipe 15^a with water supply pipe 15, which may be connected to a city main, and a branch pipe 15^b connects with the chamber a' for supplying water thereto for the purpose hereinafter described, said branch pipe 15^b being provided with a cut-off valve 15^c.

The ejector nozzle 12 is provided at its 65 upper end with a valve seat 12^a with which

cooperates a valve 16^a which is carried at the lower end of a solenoid core 16 which is actuated by the solenoid coil 17 which is preferably provided with a magnet frame 18.

A thermostat 19 within the refrigerator is used to control the current through the solenoid coils. When current is supplied to coil 17 the core is raised and the valve opened, allowing water under pressure to 75 flow from the source of supply to the ejector nozzle. The jet passing from the nozzle into the member or diffuser 13 draws air with it thereby exhausting the air from the chamber a' and hence from the refrigerat- 80 ing system.

Means are provided for automatically controlling the motor whereby it will not be started until the pressure in the system has been sufficiently reduced. To this end 85 a motor control unit 19^a is mounted on the casing 2 which is constructed as follows:

An opening in the casing communicating with the upper part of the chamber a' is closed by a flexible diaphragm 20, the center of which is connected by a link 21 with a tension spring 22, which in turn is connected to adjusting screw 23 guided in a suitable bracket and operated by thumb nut 24 to secure suitable adjustment of the 90 spring. Link 21 is also connected to one arm of a lever 25 fulcrumed at 26. The opposite arm of lever 25 has pivotally connected thereto a guide rod 28 which slidably engages at its outer end in an opening in 100 the cross bar of the switch lever 29 fulcrumed at 29^a, which switch lever carries insulated contact piece 30 designed to operate with and electrically connect contactors 31.

Stops 32 are provided to limit the movement of the switch lever. Encircling the guide rod 28 is a compression spring 27 which bears at its inner end against a stop washer carried by the guide rod and at its outer end against the cross bar of the switch lever.

When no vacuum is present in the chamber a', the pressure of the spring 22 through the lever 25 holds the switch arm in circuit breaking position. When, however, the vacuum in the system rises to a sufficient degree the pull upon the diaphragm overcomes the tension of the spring 22 swings lever 25 until the end against which spring 27 bears crosses the dead center, whereupon the pressure of said spring 27 immediately forces the switch lever or arm 29 into circuit closing position.

From the foregoing description it is believed the operation of my improved refrigerator system will be obvious, but it may be briefly stated as follows:

At the commencement of the operation water is admitted to the system through pipe 130

15^b by opening cock 15^c and flows from chamber a' through pipes 4 and 3 into the interior of the rotor. Thence it overflows through the annular passage 3^a into the refrigerator through pipe 8 where it fills first the topmost tray c, overflows into the next lower one, and so on until all the trays are filled and also the bottom of the outer container to the liquid level shown in the drawings at which time the stop cock 15^c is closed.

Electric current is now turned on which energizes the solenoid and opens the valve 12^a, starting the action of the air ejector 15 to produce vacuum in the system, it being understood that the motor circuit is broken by the motor control unit. When the proper degree of vacuum has been produced the motor circuit is closed and the electric motor 20 started which drives the rotor 5 at a high rate of speed. The vacuum within the system causes the water in the refrigerator trays to be vaporized and the rapid rotation of the rotor causes the water in the 25 rotor to be ejected through the passages 5^a into the diffuser passages 6 in the form of sheets which draws vapor from the chamber a and through the compressive action of the jets and the cooling action of the coils 30 condenses said vapor in chamber a.

The condensed water flows through pipes 4 and 3 back into the interior of the rotor. The vapor continues to rise from the trays and be condensed by the rotor until the 35 refrigerator has cooled sufficiently to cause the thermostat to break the motor circuit.

Any water accumulated in the rotor above the level of overflow passage 3^a will pass into chamber a and thence through pipe 8 back to the refrigerator trays as above described.

Having thus described my invention, what I claim is:

1. In a vacuum refrigerating apparatus, 45 a refrigerator unit having a closed chamber adapted to contain a volatilizable liquid, a closed condenser unit having a suction compartment and a condensing compartment, said condenser unit having its suction compartment only connected with said refrigerator unit, a rotary ejector arranged in said suction compartment adapted to draw vapor from said suction compartment and deliver it into said condensing compartment, and means for conveying condensed liquid from said condensing compartment directly to said rotary injector.

2. In a vacuum refrigerating apparatus, a refrigerator unit having a closed compartment adapted to contain a volatilizable liquid, a closed condensing unit having a central vapor compartment, and an annular condensing chamber, said condensing unit having said central compartment only communicating with the said compartment of

the refrigerator unit, a hollow rotor journaled in said vapor compartment having peripheral ejector discharge passages, means for maintaining a determined liquid level in said rotor, and means for returning condensed liquid from the condenser chamber to the interior of the rotor. 70

3. In a vacuum refrigerating apparatus, a refrigerator unit having a closed compartment adapted to contain a volatilizable liquid, a closed condenser unit having a central vapor chamber and an annular condenser chamber, said condenser unit having its central vapor chamber only connected with said closed refrigerator compartment, a standpipe in said central chamber having its lower end connected to the lower part of said condensing chamber to withdraw condensed liquid therefrom, a hollow rotor mounted to rotate about said standpipe and having a tubular hub spaced from said standpipe and adapted to constitute a liquid overflow, said rotor having ejector passages and the wall of said vapor chamber having diffuser passages into which said ejector passages discharge. 80

4. In apparatus of the class described, a refrigerator unit having a closed compartment adapted to contain a volatilizable liquid, a condenser unit having a central vapor chamber communicating with said closed compartment and an annular condenser chamber, a rotary ejector arranged to withdraw vapor from said vapor chamber and eject it into said condenser chamber, 95 a motor for operating said ejector, means for providing a vacuum in the system, and means governed by the action produced by the ejector for controlling the operation of the motor. 100

5. In refrigerating apparatus of the class described, a refrigerator unit having a closed compartment adapted to contain a volatilizable liquid, a closed condenser unit having a vapor chamber, and a condenser chamber, said condenser unit having said vapor chamber only connected with the closed refrigerator compartment, ejector means for withdrawing vapor from said vapor chamber and forcing it into the condensing chamber, means for returning condensed liquid from said condensing chamber to said ejector and an ejector arranged to withdraw air from said system. 115

6. In a refrigerating apparatus of the class described, a refrigerator unit having a closed compartment for a volatilizable liquid, a condenser unit having a vapor chamber communicating with said closed compartment, and having a condenser chamber, means for withdrawing vapor from said vapor compartment and compressing it in said condenser compartment, condenser coils in said condenser compartment, a water ejector for withdrawing air from said re- 120 125 130

frigerating apparatus, said water ejector being arranged to discharge its water through said condenser coils.

7. In refrigerating apparatus of the class described, a refrigerator unit having a closed compartment for aqueous liquid, a closed condenser unit having a vapor chamber and condenser chamber, the vapor chamber only being in communication with said refrigerator compartment, condenser coils in said condenser compartment, a rotary ejector in said vapor compartment, means for returning condensed aqueous liquid from said condenser compartment direct to the interior of said rotor, and automatic means for controlling the action of the ejector.

8. In a refrigerating apparatus of the class described, a refrigerator unit having a closed compartment for a volatilizable liquid, a condenser unit having a vapor chamber communicating with said closed compartment, and having a condenser chamber, means for withdrawing vapor from said vapor chamber and condensing it in the condensing chamber, an air suction device for producing a vacuum in the system, means controlled by the temperature in the refrigerating unit for governing the action of said air suction means, a motor for operating said vapor withdrawing and compressing means, and means controlled by the vacuum produced within the system for starting and stopping said motor.

9. In refrigerating apparatus of the class described, a refrigerator unit having a

closed compartment for a volatilizable liquid, a condenser unit having a central vapor chamber communicating with said closed compartment and having an annular condenser chamber surrounding said vapor chamber, there being a cylindrical wall separating said chambers provided with a thickened portion at its upper edge having diffuser passages, a hollow rotary ejector journaled in said vapor chamber having ejector passages aligning with said diffuser passages, and a pipe leading from the bottom of the condenser chamber to the interior of said rotor.

10. In refrigerating apparatus of the class described, a refrigerator unit having a closed compartment for a volatilizable liquid, a condenser unit having a central vapor suction chamber and an annular condensing chamber, and a cylindric wall between said chamber having an annular series of diffuser passages in the upper part thereof, a hollow rotor rotatably mounted in said vapor chamber and having an enlarged upper portion provided with ejector passages aligning with said diffuser passages, a pipe connection leading from the closed refrigerator compartment to the portion of the vapor casing outside the rotor, and a pipe connection from the condenser chamber to the interior of the rotor.

In testimony whereof, I affix my signature.

EDWIN R. SAGE.
